C. A. KEARNS

ARTIFICIAL BAIT

Filed April 27, 1926

Patented Dec. 14, 1926.

1,611,117

UNITED STATES PATENT OFFICE.

CHESTER A. KEARNS, OF EDISON, OHIO.

ARTIFICIAL BAIT.

Application filed April 27, 1926. Serial No. 104,980.

This invention relates to certain improvements in artificial bait and it is an object of the invention to provide a device of this kind comprising a conventional plug together with a covering adapted to be detachably applied to said plug to provide the desired lure.

Another object of the invention is to provide a bait of this kind wherein a stretchable cover is adapted to be snugly engaged with the plug and wherein said plug and cover are provided with coacting means to effectually maintain the cover in applied position yet at the same time readily permitting removal of the cover.

The invention consists in the details of construction and in the combination and arrangement of the several parts of my improved artificial bait whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a view in side elevation illustrating an artificial bait constructed in accordance with an embodiment of my invention;

Fig. 2 is a view in plan of the cover as herein disclosed flattened out;

Figure 3 is a view in bottom plan of the plug as comprised in my improved bait;

Figure 4 is a sectional view taken substantially on the line 4—4 of Figure 1.

As disclosed in the accompanying drawing, P denotes the plug of an artificial bait of requisite configuration or design and which is provided along its bottom surface with the parallel grooves 1.

A cover C is adapted to be snugly engaged around the plug P and this cover C is of any desired color and is of rubber or other stretchable or elastic material. This cover C is provided with the rear extensions 2 in simulation of a fish tail and which are preferably disposed beyond the rear of the plug P and also have affixed thereto the strips 3 in simulation of the fins or other parts of a fish.

The cover C is in the form of a sheet and

the longitudinal marginal portions or ends of the cover C are secured to elongated and substantially rigid strips 4 preferably of metal and which strips are adapted to be received within the grooves 1 to effectively maintain the cover C in applied position upon the plug.

In applying the cover C, one of the longitudinal marginal portions thereof is engaged with a groove 1 and whereupon pull is imposed by grip on the opposite longitudinal marginal portion to sufficiently stretch the cover C to assure its extending entirely around the plug. At the same time turning or rolling motion will be imposed to the plug, thus assuring the same being properly enveloped within the cover and then the second longitudinal marginal portion of the cover is properly engaged within the second groove 1.

In practice, the fisherman will take along covers C of different characters or types, that is to say, of different colors or otherwise having individual characteristics, whereby with the use of not more than one or two plugs he will be able to produce lures of various kinds. It is also to be noted that the extensions 2 of the cover C simulating the tail of the fish serve effectually to shield the rear hook H and thus materially increasing the efficiency of the device as a lure.

From the foregoing description it is thought to be obvious that an artificial bait constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. An artificial bait comprising, in combination, a plug, a cover sheet of stretchable material for said plug, and means for detachably attaching the ends of the cover sheet to the plug for holding the cover sheet to the plug.

2. An artificial bait comprising, in combination, a plug, a cover sheet of stretchable material for said plug, and means for de-

tachably attaching the ends of the cover sheet to the plug for holding the cover sheet to the plug, said cover having rear extensions simulating the tail of a fish when the cover is applied.

3. An artificial bait comprising, in combination, a plug having grooves in a portion thereof, a cover adapted to substantially envelope the plug, and substantially rigid

members carried by the side marginal portions of the cover adapted to be received within the grooves of the plug to hold the cover in applied position, said cover being stretchable.

In testimony whereof I hereunto affix my ¹⁵ signature.

CHESTER A. KEARNS.
